Nelson A. Hallauer
his ATTORNEY

Clarence Taylor.

UNITED STATES PATENT OFFICE.

WALTER CHANDLER KNAPP, OF ROCHESTER, NEW YORK, ASSIGNOR TO LIBERTY BREAD-SLICER INC., OF ROCHESTER, NEW YORK, A CORPORATION OF NEW YORK.

SLICING MACHINE.

1,417,843.

Specification of Letters Patent. Patented May 30, 1922.

Application filed May 5, 1920. Serial No. 378,943.

To all whom it may concern:

Be it known that I, WALTER CHANDLER KNAPP, a citizen of the United States, and a resident of Rochester, in the county of Monroe and State of New York, have invented certain new and useful Improvements in Slicing Machines; and I do declare the following to be a full, clear, and exact description of the same, taken in connection with the accompanying drawings, forming a part of this specification.

My invention relates to slicing machines and is in the nature of an improvement on the device disclosed in my pending application for patent for slicing machines, Serial Number 323,166 filed September 11, 1919, which has matured in Patent #1,380,393 dated June 7, 1921.

In said machine, rolls or biscuits are fed continuously over the edge of a revolving circular knife. The object of my present invention is to provide improved means for feeding rolls of various sizes to the machine. A further object of my invention is to provide means for more uniformly slicing the rolls, than is possible with a machine such as disclosed in my pending application above identified. More specifically the object of my present invention is to provide the chute or trough in which the rolls are fed with adjustable means for guiding the rolls to the knife, means being provided thereon for preventing the rolls from fouling against the edge of the knife.

Referring to the drawings:

Fig. 1 is a side elevation of a slicing machine, one side of the chute being sectioned away to show my improvements in position therein.

Fig. 2 is a plan view of the same with the top of the chute sectioned away to show my improvements therein.

Fig. 3 is a perspective view of the guide plate removed from the machine, and

Fig. 4 is a substantially transverse section through the chute on the line 4X—4X Fig. 2.

The machine illustrated comprises a cylindrical base or support 1, in which is mounted a motor 2 having a vertical shaft 3 to the upper end of which is secured a circular knife or blade 4. Pivoted at 5 to the top of the base is the chute or trough 6 which is adapted to extend across the top of the base and has one wall thereof slotted as

at 7 to provide a clearance for the knife. The opposite side of the chute is provided with a projection 8 to provide a clearance for the knife when the chute is adjusted to slice the rolls completely through. The chute is adjustable about the pivot 5 to vary the extent to which the knife projects into it for cutting the rolls completely in two or only partly, the forward end thereof resting on a slotted projection 9 to which it is secured in adjusted position by means of a bolt 10 projecting through the slot in the projection 9. A plate 11 is adjustable in the chute toward and from the knife to vary the thickness of the slice. The plate 11 is supported on bars 12 having threaded ends projecting through slots in the side walls of the chute and receive thumb nuts 13 by which the plate 11 is secured in adjusted position.

The parts above described are substantially the same as those described in my pending application above referred to. My present invention comprises a forwardly extending outwardly flared member 14 secured to or made integral with the plate 11, from which the rolls are fed into the chute. If desired the member or support 14 may be formed with a flange 15 around its outer edge to retain the rolls thereon. Secured to the flared support 14 is a guide plate 16 extending forwardly toward and over the knife and is cut away as at 17 to provide a clearance for the knife. The guide 16 is adjustable on the chute and for this purpose the chute or flared end thereof is slotted as at 18 to receive the shouldered bolts or screws 19 which extend through openings in a flange 20 formed on the base of the rear end of the guide and through the slots 18 and receive the butterfly nuts 21 on their outer ends. By loosening the nuts 21 the guide 16 can be adjusted along the slots 18 and secured in adjusted position by again tightening the butterfly nuts. Adjustment of the guide along the slots 18 moves the guide from and toward the inner wall of the chute and insures the proper feeding of the rolls between the guide and the outer wall of the chute.

In the form of my invention illustrated herein, the guide plate 16 is formed with an angle at the point 25 so that the rear end of the guide will be kept substantially parallel with the flared side of the support 14.

Means are also provided for holding the rolls in proper position as they come in contact with the knife to prevent fouling. Said means comprises a plate 22 operated by gravity and adapted to rest on successive rolls at the time when they are engaged by the knife. The plate or finger 22 is secured to a rod 23 pivoted at 24 to the guide 16 and extends forwardly and downwardly into contact with the surface of the knife or a roll in position to be engaged by the knife. As the rolls are successively fed forward, the plate 22 rests upon or engages each roll as it comes into contact with the knife and holds it in contact with the plate 11 during the slicing operation, thus insuring a uniform thickness of the slices cut from successive rolls.

Having described my invention, what I claim and desire to secure by Letters Patent is:

1. In a slicing machine, the combination of a knife, a chute for directing the material to be sliced to the knife, and a plate pivoted in the chute and extending forwardly and downwardly over the knife to engage the material to be cut as it is fed into engagement with the knife.
2. In a slicing machine, the combination of a knife, a chute for directing the material to be sliced to the knife, a guide ad-

justable transversely of the chute for adapting the chute to material of different sizes, and means mounted on said guide for holding the material in contact with the bottom of the chute as it moves into engagement with the knife.

3. In a slicing machine, the combination of a knife, a chute for directing the material to be sliced to the knife, a guide adjustable transversely of the chute for adapting the chute to material of different sizes, and a plate pivoted on said guide and adapted to rest on the material as it moves into engagement with the knife.

4. A slicing machine, the combination of a knife, a chute for directing the material to be sliced to the knife, a support for the material having a flared forward end adjustably supported in said chute, and a guide on said support adjustable transversely of the chute.

5. A slicing machine, the combination of a knife, a chute for directing the material to be sliced to the knife, a support for the material having a flared forward end adjustably supported in said chute, a guide on said support adjustable transversely of the chute, and a member pivoted on said guide and adapted to engage the material being sliced.

WALTER CHANDLER KNAPP.
